DRESSING DEVICE FOR GRINDING WHEELS

William Walter Hopkins, Springfield, Mass.

Application May 17, 1945, Serial No. 594,352

5 Claims. (Cl. 125—11)

1

This invention relates to an improved dressing device for grinding wheels.

In the prior practice, an industrial diamond is mounted in a support, the grinding wheel is rotated, the diamond is moved back and forth on a curve, corresponding to the cross sectional shape of a desired dressing, the wheel and diamond are moved against each other by small steps, and the diamond grooves the wheel step by step until the desired form is made. The form is an annular groove having a precision cross sectional shape. This is all very well known. In some kinds of work, a special problem is presented to the skilled man wanting to dress a wheel to a shape that is not adapted to be made by the most usual method. For example, the dressing of a small groove to be made in the grinding wheel, with a semi-circular cross section having a $\frac{1}{32}$ inch radius presents a special problem. The radius is too small to use the most usual dressing method. When precision is needed in such an instance, one way to get it is to shape a diamond for the desired cross sectional curve and press the shaped tool (diamond) radially against the grinding wheel to dress the latter. It is an expensive way and not only that, it is far from a convenient way because such a small and expensive tool quickly gets defective. The diamond even when welded to its holder snaps off after little use and the precision shape is worn away after little use.

With these circumstances as a background, I have invented a new and inexpensive device to do the work of dressing. It is particularly adapted to convenience and precision in making dressings of small cross sectional shapes as in the specific example already given, and it is also adapted for making dressings of comparatively large cross sectional shapes.

The new device, its mode of operation and the results will be disclosed and referred to in connection with the accompanying drawings.

Fig. 1 is a side view of the device and indicates the relation of the work to the cutting diamond and a way of feeding the work in the operation;

Fig. 2 is a view looking at the device from the right in Fig. 1;

Fig. 3 is a section on line 3—3 of Fig. 1;

Fig. 4 is a detail section on line 4—4 of Fig. 1;

Fig. 5 is a section on line 5—5 of Fig. 1;

Fig. 6 is a view similar to Fig. 2 but with parts in different positions;

Fig. 7 is a section taken along the same line as Fig. 5 but with the parts shown in the same relative position as those shown in Fig. 6;

2

Fig. 8 is a section taken along the same line as Fig. 5 but with the parts in one extreme position; and

Fig. 9 is an end view, the same as Fig. 2, with parts broken away. The full line position shows the tool support against a stop and the diamond point scribing an arc in a grinding wheel, partially shown, and the dotted lines show the diamond point at one extreme end of the scribed arc and its tool support against a stop to prevent it from hitting the grinding wheel.

In the example of the invention shown by these drawings:

The diamond cutting element 1 is welded on the end of holding rod 2. This is slidably mounted for adjustment in another holding rod 3, the adjustment being held by set nut 4. Rod 3 in turn is mounted for an adjustment held by set nut 5 in swinging arm or tool support 6. The center on which arm 6 swings in one way, to be described, is the axis of a cylinder 7, see Fig. 5, which is mounted like a shaft in the vertical part 8 of the frame, which frame includes the base plate 9. The arm 6 has a shaft 10 fixed to it and extending rearwardly. Shaft 10 passes through an eccentric bore 11 of cylinder 7. Shaft 10 extends rearwardly through bore 11 and beyond the cylinder 7. At its rear end a collar 12 is fastened by set screws 13. The collar 12 and the shaft 10 must move together. The collar 12 is part of a friction clutch. This clutch is made up of collar 12 which on its inner face, has an annular series of recesses and in each recess a coiled spring is bottomed. The springs press against the second part of the clutch which part is disc 14 mounted on shaft 10 so as to turn with it and slide relatively, being feathered on the shaft for this purpose. Disc 14 has two pins 14' on its outer face engaged with opposite holes on the inner face of collar 12. Thus the disc under spring pressure may move axially of shaft 10 between collar 12 and the adjacent face of frame part 8, and both clutch parts must turn with shaft 10. The clutch is assembled and mounted as indicated so that there is considerable friction to the turning of shaft 10 in cylinder 7 because of the clutch parts which turn with the rod. The friction is between disc 14 and frame 8.

A spring pressed detent pin 15 is provided on the outer face of cylinder 7. It rides in a hole in this face with a spring tending to keep it in outer position but permitting it to be pushed inwardly. A radial V-shaped groove 16, on the inner face of disc 14, cooperates with pin 15, as will be described.

A handle 17, in the form of a radius rod fastened to cylinder 7, and extending through the slot shown in the frame 8, see Fig. 1, provides means for rocking the cylinder 7 in its frame bearing and such rocking is back and forth about the cylinder axis.

As stated before, shaft 10 is carried in the eccentric bore 11 of cylinder 7. So, when the cylinder 7 is rocked back and forth by handle 17, the rocking axis being the cylinder axis, then shaft 10 will have its axis moved back and forth over an arc whose radius is the amount of the eccentricity or offset of the shaft 10 axis with the cylinder axis. This is indicated by the center lines in Fig. 1 and the centers in the other figures.

With the construction so far described, one grinding wheel dressing operation will be described. The diamond 1 is adjusted so its cutting point coincides with or is on the axis of shaft 10 and fixed there. A flat portion on the upper side of block 6 adjacent its end may be made a precision base for setting the diamond point to this adjustment. It is desired to provide for great precision in the setting stated. The handle 17 may have a line to coincide with a line on frame 8 when the handle is exactly vertical, at which time the rod 2 holding the diamond is also vertical, detent groove 15 is vertical, and detent 15 is in its groove 16. At this time the axis of shaft 10 is set above axis of cylinder 7 and on a vertical line passing through both axes. This is the starting position of the device. When the device is set in this position, the grinding wheel to be dressed is moved down by adjustment of the work holder H indicated in Fig. 1, until the diamond is just touching the periphery of the grinding wheel. It is from this position that the grinding wheel will be fed, by indexing feeding means, indicated at I, to move the work toward the tool (diamond) in precision steps, for example steps of five thousandths of an inch each. The result of the preparation setting of the work and the tool for operation is indicated generally in Fig. 1. It will be understood that means not shown will rotate the grinding wheel.

From the preparation just described the operation will be to move the tool in an arc away from the work by turning the handle 17. Then the work holder moves the grinding wheel down with a precision step. The grinding wheel is rotated. Then the handle 17 is rocked to swing the tool against the work and back and forth, in an arc. This arc has a radius equal to the offset of shaft 10 from axis of cylinder 7. The diamond will dress an annular groove in the wheel with depth equal to the precision measurement of one step in feeding the work against the diamond. This of course assumes that the grinding wheel has a flat periphery to start the sinking of a groove in it. Between each two feeding working steps of the work holder, handle 17 is rocked enough to dress an annular groove to the depth of one feeding step. Of course the depth of the groove will gradually increase with the addition of each feeding step and the following dressing step. If we assume that the radius of the arc in which the diamond is swung in each such dressing step is a large enough radius, the whole dressing of the groove may proceed as stated until it has a depth equal to such radius. Or if we assume that the groove to be finished is a shallow one, in the example it is $\frac{5}{32}$ inch, of less depth than the said radius, there will be no special difficulty, as by the tool holder not having room to clear the

sides of the groove when it gets to the bottom of the shallow depth. The special difficulty with small deep grooves will be further explained. The operation of the device thus generally described is to show that the device is adapted to dress the groove in the grinding wheel with great precision. It is useful for that purpose.

The device, however, is particularly adapted in a special way for dressing a grinding wheel with one or more small grooves, those grooves with a small radius and relatively deep or deep enough to cause trouble when the operation is only on the order of that above described. The trouble referred to is the difficulty in getting the tool holder to clear the sides of the groove being dressed.

The device is adapted to do such particular work by the provisions now to be explained.

The swinging arm or support 6 has two stops 18, one on each side. They cooperate with adjustable stops 19 one on each side of frame part 8. The latter has a shelf 20 for each stop 19. A convenient construction for this is to thread stop 19 through shelf 20 and supply a lock nut 21 to hold the vertical adjustment of stop 19. By loosening nut 21, stop 19, screwed in shelf 20, may be given an accurate adjustment by a screw driver applied from the top and nut 21 then tightened. Thus the length of the arc in which arm or support 6 may swing is limited by these stops 18 and 19. This limited length has reference to the operation already described. That operation if tried out to make a full semi-circular groove of $\frac{5}{32}$ inch radius would run into the difficulty before mentioned. When the groove being dressed gets near its full depth there is not room for the tool and its holder to clear the sides of the groove. This will be seen from Fig. 9, using center C of cylinder 7 for swinging the tool. So the length of the arc is determined by the stops to prevent the continued mode of operation above described and just before the tool would otherwise fail to clear the sides of the groove being dressed.

When the first way of operation is thus stopped, the device will automatically change its way of operation to continue the dressing. The second stage or modified operation is for the purpose of continuing the dressing of the small groove without any interference by the sides of the groove in clearing the tool. This will now be explained.

Up to the time that the tool will continue to dress the small groove to a gradually increasing depth without needing an arc greater than that determined by the stops, the cylinder 7 and shaft 10 are rocked as a unit by handle 17 (Figs. 6 and 7). When the stops are engaged, handle 17 can by some extra force continue to rock cylinder 7 alone and further over on each side (Fig. 8). The stops act to prevent shaft 10 rocking as before with cylinder 7 and as if these two pieces were one. The friction clutch and its detent construction, holds them together, as if they were one until the stops cause the clutch to slip. Then cylinder 7 can move without carrying shaft 10 and its tool support 6 in the way it did in the first way. The detent 15 is moved out of its groove 16 (Fig. 8) when handle 17 moves cylinder 7 after stops 18, 19 are engaged to stop shaft 10. Cylinder 7, however, carries shaft 10 and its arm 6 in a new way for the second stage. This new way is to carry shaft 10, support 6, and the tool rods 2 and 3 bodily as a unit, but not on C as the center. When its first stage movement with cylinder 7 is stopped, the cylinder movement is

continued. As shaft 10 cannot continue in the old way, the cylinder must cause the shaft 10 to move in a new way. The friction clutch connecting these two parts, cylinder 7 and shaft 10, permits a relative movement between them. This movement is one of relative rotation of shaft 10 in the offset bore 11 of cylinder 7. The latter of course continues its movement on its own axis. The relative rotation of shaft 10 in its offset bore, or bearing, of course, is on the axis of such bearing. Such relative rotation causes the axis of shaft 10 to move downwardly on an arc. The parts connected with shaft 10, that is swinging arm or support 6, the tool holder rods 2 and 3, and the diamond point tool, all move downwardly. This is indicated between full and dotted line positions in Fig. 9. In this movement the diamond point is still being swung on the center C of cylinder 7, over its cutting arc as before. Its tool holder is being translated bodily in a path and every point of shaft 10, arm 6, rods 2 and 3, as well as the diamond point all take the downward path. This is the path required for the diamond point to finish cutting the semi-circular or other deep groove by small increments and for the tool holder to clear the sides of the groove. This result follows because the tool holder is drawn down out of the way as the diamond point is held to the line of work, see Fig. 9. This line is the continuation of the same arc started by merely swinging the tool on the one center C. In the deep type of small groove such mere swinging is stopped automatically just before the point of the arc, where the tool holder will interfere. Then as stated the diamond point and its tool holder is given a translating movement in which all parts are drawn downwardly, while the diamond point follows to finish the arc shaped cut.

Reference to Fig. 9 will indicate the operation from a more technical viewpoint.

The arc of the dressing within the angle D, is the same as the arc made in the first way of operation swinging the diamond point back and forth from center C. When the wheel is dressed with such an arc and to the depth of its center from its chord, the way of operation is changed. It is assumed that the ends of said arc represent the points from which increased dressing to make the arc deeper and longer will risk an engagement of the sides of the tool or tool holding rod with the work. Of course such points are chosen with a real margin of safety to avoid such bad engagement. It is at these end points of the example, where the way of operation is caused to be changed by stops 18 and 19 as before described. Now it will be seen from Fig. 9 that the important thing is for the diamond point 1 to continue to swing over the same arc as before and extend the arc to make the dressing deeper. It will also be seen that if the whole operation were attempted by swinging the tool holder on center C the tool sides would engage the work and interfere with making the deep small groove. It will finally be seen that this is prevented by a bodily movement of the tool sides downwardly and away from the groove while the diamond point is moved along the extended portions of the arc beyond the sides of angle D in Fig. 9.

In this respect the device automatically changes its way of operation between the first and second dressing parts of the whole operation to make a small deep groove. All the operator need do, after the original setting of the device as in Fig. 1, is to swing handle 17 back and forth and feed

down the work against the tool. The cylinder 7 and shaft 10 will be moved to make exactly the right arc in the dressing.

Within a considerable scope, the radius of the groove to be dressed may be changed and the same device used. That is the same parts may be used to make different size grooves except the part represented by cylinder 7. This cylinder 7 of the example is specially made for a groove of $\frac{5}{8}$ inch radius. The cylinder alone controls the groove size as all the other parts are adapted for use in making different sizes. When a different size groove is wanted, another cylinder is supplied. It is in all respects like cylinder 7 except for the amount of offset between its axis and the axis of the bore 11 through the cylinder, see Fig. 5. This offset is made different and to correspond with the different radius wanted for the groove to be dressed. It would be made $\frac{4}{32}$ inch or $\frac{1}{8}$ inch to make a groove smaller than the example of $\frac{5}{8}$ inch. The device described with a set of similar cylinders corresponding to groove sizes wanted is the way in which the device would be put into the shop. The friction clutch parts 12 and 14 are readily removable from shaft 10. Supporting arm 6, shaft 10, and cylinder 7 are readily removable from the frame as a unit by movement to the right in Fig. 1. Then one cylinder such as 7 with one position of offset bore 11 may be substituted for the cylinder with a differently positioned offset bore 11, and the parts reassembled to make a different size groove than before. While a good deal of description of the device and its use seems desirable for its disclosure, there are not many parts, there are no real complications, and the whole device is economical for manufacture and adapted for use in precision dressing of grinding wheels. The only skill required is that of precision in setting the parts for work and that is plain measurement skill. The operation after it is once set up does not require skill, but the mere swinging of handle 17 and the intermittent feed of the work holder between cutting steps.

In the operation above described I consider the function of detent 15 and groove 16 very helpful. When handle 17 has swung over for stop 18 on support 6 to engage stop 19, the engagement occurs as the arc of angle D, Fig. 9, is finished. As handle 17 swings further over the arc is extended down to the end as seen in Fig. 9. In this movement of the tool from full to dotted line positions the tool holder 2-3 is not swinging on point C. When the handle 17 is swung back to carry the diamond over the whole arc to the other corner, it is important to start swinging the tool holder 2-3 on center C about when it reaches full line position of Fig. 9. Otherwise the tool sides would begin to interfere with the work. The tool holder begins to swing on center C in the dressing operation from left to right as the holder reaches the full line position shown. This action is insured by detent 15 engaging in groove 16 at just about this time. Then the parts, shaft 10 and cylinder 7, will not slip relatively as they might otherwise do and miss the time for beginning the swing on center C to do the work right.

Having disclosed the invention I claim:

1. A device for dressing grinding wheels, comprising a cylindrical body provided with an end to end cylindrical bore with the axis of the bore offset by an amount equal to the desired radius of a groove to be dressed in a grinding wheel and said axis also parallel to the cylindrical body

axis, a tool support to hold a cutting tool point on the axis of said bore to swing in a plane at right angles to the line of such axis, a shaft mounted in said bore and carrying said tool support for its swinging movement, a frame with bearing means to mount said cylindrical body, means to rock the cylindrical body about its axis to move the axis of said shaft in an arc having a radius equal to the amount of the shaft axis offset from the cylindrical body axis.

2. A device for dressing grinding wheels, comprising a cylindrical body provided with an end to end cylindrical bore with the axis of the bore offset by an amount equal to the desired radius of a groove to be dressed in a grinding wheel and said axis also parallel to the cylindrical body axis, a tool support to hold a cutting tool point on the axis of said bore to swing in a plane at right angles to the line of such axis, a shaft mounted in said bore and carrying said tool support for its swinging movement, a frame with bearing means to mount said cylindrical body, means to rock the cylindrical body about its axis to move the axis of said shaft in an arc having a radius equal to the amount of the shaft axis offset from the cylindrical body axis, said cylindrical body, shaft, and frame being readily separable so as to substitute a similar cylindrical body with a bore having another amount of offset from the body axis to change the radius of the arc for movement of the shaft axis.

3. A device for dressing grinding wheels, comprising a cylindrical body provided with an end to end cylindrical bore with the axis of the bore offset and parallel to the cylindrical body axis, a tool support to hold a cutting tool point on the axis of said bore to swing in a plane at right angles to the line of such axis, a shaft mounted in said bore and carrying said tool support for its swinging movement, a frame with bearing means to mount said cylindrical body, means to rock the cylindrical body about its axis to move the axis of said shaft in an arc having a radius equal to the amount of the shaft axis offset from the cylindrical body axis, friction clutch means normally preventing relative turning movement between the cylindrical body and the shaft, stop means adapted to limit the length of arc in which the cylindrical body and shaft may rock as a unit and means including said stop means, adapted to permit a further rocking movement of the cylindrical body beyond the ends of such arc to cause relative turning movement of the shaft in its offset bore while maintaining the axis of such shaft on the line of the limited arc as extended beyond its aforesaid limited length.

4. A device for making annular grooves on the circular face of a disc, said device comprising a frame with a vertical portion having a horizontal bearing, a precision made cylinder mounted to

rock in said bearing, a radial handle on the cylinder to rock it, a shaft mounted with its axis precisely offset from the axis of the cylinder and extending through the cylinder for rotation, a friction clutch mounted between the shaft and cylinder and adapted to normally prevent such rotation, and to permit movement of said handle to rock the cylinder and shaft as a unit, a tool support connected to said shaft having

5 means to hold the point of a cutting tool exactly on the axis line of said shaft, cooperating stops on said frame and tool support, such stops being adjustable to determine the limits of a rocking movement of cylinder and shaft without relative rotation, whereby upon extended movement of said handle said clutch slips for the cylinder to rock further and for the shaft to be turned relatively to the cylinder whereby the shaft axis and said cutting tool point can continue to describe an arc of the same radius and the tool support can be moved bodily to direct the sides of the tool into positions which will not interfere with the cutting operation substantially as described.
